UNITED STATES PATENT OFFICE.

JOSIAH B. KING, OF TORONTO, CANADA.

DESIGN FOR A BADGE.

SPECIFICATION forming part of **Design No. 29,958, dated January 10, 1899.**

Application filed July 20, 1898. Serial No. 686,476. Term of patent 14 years.

To all whom it may concern:

Be it known that I, JOSIAH BROWN KING, a subject of Her Majesty the Queen of Great Britain, residing at the city of Toronto, in the 5 Province of Ontario, in the Dominion of Canada, have invented and produced a new and original Design for a Badge, of which the following is a specification, reference being had to the accompanying drawings, forming part 10 thereof.

My invention is a badge; and it consists of a series of letters and links intertwined and connected together.

In the accompanying drawings, Figure 1 15 is a face view of my design, and Fig. 2 is a section on line 2 2 of Fig. 1.

As shown in the drawings, the design consists of the letters I O O F, arranged in the order named and alongside of one another,

these letters having intertwined therewith a 20 series of links, the first link including in its circuit the letter I, a part of the letter O, and a part of the second link. The second link includes in its circuit a part of the first link, a part of the first letter O and part of the 25 second letter O, and a part of the third link, and the third link includes in its circuit a part of the second link, a part of the second letter O, and the letter F.

I claim—

The design for a badge as herein shown and described.

In witness whereof I have hereunto set my hand in the presence of two witnesses.

J. B. KING.
